UNITED STATES PATENT OFFICE

BERNHARD SOPHUS FAITH ELL, OF SPANGA, SWEDEN, ASSIGNOR TO TELEFONAKTIE-
BOLAGET L. M. ERICSSON, OF STOCKHOLM, SWEDEN, A COMPANY OF SWEDEN

DRYING AND IMPREGNATING OF CABLES

Application filed January 6, 1931, Serial No. 507,037, and in Sweden February 7, 1930.

For drying and impregnating electrical cables, particularly high tension cables, hermetically sealed pots or heating vessels are commonly used in which the cables are placed and which may be evacuated or filled with oil. In order to be more easy to handle, the cables are then generally put in crates or perforated boxes which are inserted into the heating vessel. After the latter has been closed it is evacuated to remove the humidity from the cable, heat being simultaneously supplied by external heating of said vessel by means of steam or electricity. After the cable in this manner has been completely dried the heating vessel is filled with oil which is maintained at an excess of pressure of about four atmospheres. After completed impregnating the oil is tapped off and the cable crates removed whereupon the vessel may be again used for drying and impregnating a new set of cables.

Apparatus of said kind are, however, comparatively expensive and are also uneconomical in operation. A cause of the bad economy is due to the fact that the heat supplied to the cable during the evacuating period only takes place through radiation which results in a loss of heat and delays the heating of the cable. Another fact, which cooperates in increasing the costs, is that to the heating vessel a quantity of oil is supplied which is several times greater than the quantity required for impregnating the cables. The remaining oil, which during the impregnating period has been considerably deteriorated in regard to its electrical properties, must then be subjected to a special treatment before it may again be used for impregnating purposes.

The present invention has for its object to eliminate said inconveniences and consists substantially therein that the cable crates proper are formed as containers adapted to be sealed hermetically and to be evacuated and filled with oil. One or more cable containers designed in this manner may be inserted into a heating vessel in similar manner as the cable crate in the known arrangement in order to heat the cable and the oil. By such a disposition the advantage is af-

firmed that the heating vessel no longer need to be designed to withstand the vacuum or excess pressure respectively required for the drying and the impregnating procedures for which reason said vessel may be made cheaper. Further the heat supply to the cable may take place more efficiently by that the cable containers are disposed in a liquid bath whereby a greater heat economy and a shorter drying time is obtained. Said arrangement has further the advantage that the quantity of superfluous impregnating oil may be considerably reduced as only the cable container need to be filled with oil. If the cable container according to the invention is made annular the difference between its volume and the volume of the cable may be reduced to an insignificant value so that only a very small quantity of superfluous oil will remain after each impregnating procedure.

The invention will be more closely described with reference to the accompanying drawing showing an apparatus according to the invention in cross section. The heating vessel is an annular plate vessel 1 provided with an annular detachable lid 2. In the shown example the vessel is for the purpose of heating provided with steam pipes 3 disposed close to the bottom and the cylindrical side walls. The vessel as well as the lid is provided with a heat insulating covering 4 and 5 respectively. In the embodiment shown on the drawing the vessel 1 is adapted to accommodate only one cable container 6. The latter consists of an annular plate vessel which, upon being inserted in position in the heating vessel, rests upon a number of bars 7 disposed on the bottom of the vessel. The cable container 6 is provided with an annular lid 8 by means of which the container may be hermetically sealed. At two diametrically opposite points the lid is provided with connecting pipes 9, 10 for connecting the container on the one side to an evacuating device 11 and, on the other side, to an oil container 12. The pipes 9, 10 extend through bushings 13, 14 in the lid 5 and are connected to the evacuating device 11 and to the oil container 12 respectively.

through pipe lines 19, 15 including shut off valves 16, 17.

- After the cable 18 has been rolled up in the cable container 6 so that it nearly fills the entire container, the latter is placed in position in the heating vessel 1 whereupon the lids 8 and 2 are secured in position and the pipes 9, 10 connected to the pipes 19, 15. The vessel 1 contains preferably oil in such a quantity that the oil level reaches to the upper edge of the container 6. Thereupon the communication is opened with the evacuating device 11 so that the vacuum required for drying the cable is formed in the cable container. During the evacuating period the cable is heated by steam circulating through the pipes 3 the heat transfer to the cable being mediated by the oil in the vessel 1 whereby the cable is rapidly heated. After completed drying the valve 17 is initially opened so that the cable container 6 is gradually filled with oil whereupon the valve 16 is shut. During the subsequent impregnating period the oil in the cable container 6 is preferably held under an excess pressure of about four atmospheres. At the same time the impregnating oil is held at a suitable temperature by supplying heat from the heating vessel. After completed impregnating the valve 17 is shut whereupon the cable container may be removed after the lids 2 and 8 have been detached and lifted.

I claim:

1. An apparatus for drying and impregnating cables, consisting of a heating vessel, a cable container placed inside said vessel and adapted to be separately closed up hermetically, means in said heating vessel for heating the cable container externally, an oil container, an evacuating apparatus, conduits connecting the cable container with said oil container and evacuating apparatus, and means for shutting off the cable container alternately from the oil container and the evacuating apparatus.

2. An apparatus for drying and impregnating cables, consisting of a heating vessel, a cable container placed inside said vessel and adapted to be separately closed up hermetically, heating means for heating the cable container externally, a heat transferring fluid in the space between the walls of the heating vessel and the cable container, an oil container, an evacuating apparatus, conduits connecting the cable container with the oil container and the evacuating apparatus, and means for shutting off the cable container alternately from the oil container and the evacuating apparatus.

3. An apparatus for drying and impregnating cables, consisting of an annular cable container, an annular cover for said container by means of which the container may be closed up hermetically, a heating mantle for said container covering the bottom and the inner and outer side walls of the container, an oil container, an evacuating apparatus, conduits connecting the cable container with said oil container and evacuating apparatus, and means for shutting off the cable container alternately from the oil container and the evacuating apparatus.

4. An apparatus for drying and impregnating cables, consisting of an annular heating vessel, an annular cable container placed inside said heating vessel and adapted to be closed up separately, heating means in the annular space between the walls of the heating vessel and the cable container, an oil container, an evacuating apparatus, conduits connecting the cable container with the oil container and the evacuating apparatus, and means for shutting off the cable container alternately from the oil container and the evacuating vessel.

In testimony whereof I affix my signature,
BERNHARD SOPHUS FAITH ELL,
